UNITED STATES PATENT OFFICE

KARL GROSZ, OF BUDAPEST, HUNGARY

DESIGN FOR A SHOE

Application filed October 4, 1932, Serial No. 45,211, and in Austria June 23, 1932. Term of patent 3½ years.

To all whom it may concern:

Be it known that I, KARL GROSZ, a Hungarian subject, whose post office address is 11 Rombach-ucca, Budapest VII, Hungary, have invented a new, original, and ornamental Design for a Shoe, of which the following is a specification, reference being had to the accompanying drawing, forming part thereof.

Fig. 1 is a side view of a shoe showing my new design; and Fig. 2 is a diagrammatic outline across the vamp of the shoe.

I claim:—

The ornamental design for a shoe, as shown.
KARL GROSZ.
